UNITED STATES PATENT OFFICE.

CHARLES C. BEERS, OF NEW YORK, N. Y.

PROCESS OF AND APPARATUS FOR AMALGAMATING METALS.

SPECIFICATION forming part of Letters Patent No. 244,028, dated July 12, 1881.

Application filed June 14, 1880. (No model.)

To all whom it may concern:

Be it known that I, CHARLES C. BEERS, a citizen of the United States, residing in the city, county, and State of New York, have invented 5 certain new and useful Improvements in Processes of and Apparatus for Amalgamating Metals, of which the following is a specification.

My improvements relate to the extraction of 10 gold and other metals from quartz and other foreign substances by amalgamation with mercury.

In my improved process I introduce the charge into the body of the mercury in the amalgamating-vessel at two or more points, 15 from pipes which enter radially, and which eject the charge upward. I also treat the charge, after it has passed through the first amalgamating-vessel and had all its free gold or metal extracted, and before it enters the sec- 20 ond amalgamating-vessel, with a solution of potassium cyanide, to enable the mercury to combine with the remaining metal with greater freedom.

I am aware that potassium cyanide has been 25 tried in amalgamating processes, but not in this manner. It renders the process too costly to treat the entire charge with the cyanide, and it is not needed in the first vessel where more than one vessel is used. The clean or free 30 gold will combine readily without aid, but that which is contaminated with sulphides and sulphurets is much benefited by the cyanide treatment.

Heretofore in apparatus of this character 35 more than one amalgamating-vessel have been employed, and various methods of forcing the charge or pulp into the amalgamating vessel or vessels have been adopted, such as pumps and steam-injectors. The charge has also been 40 introduced into the body of the mercury in various ways. In some cases it has been introduced through one pipe at the side, in others from one pipe at the bottom opening upward, in others still a central or axial pipe has been 45 employed with lateral outlets at the bottom. None of these, however, as I believe, fulfill the conditions of perfect distribution, although various forms of gauze and perforated dia- 50 phragms have been employed to break up the incoming current of pulp.

In carrying out my invention, I prefer to em- 55 ploy the apparatus which I will now describe

with reference to the accompanying drawings, in which—

Figure 1 is a sectional elevation taken 55 through the axes of the amalgamating-vessels, and Fig. 2 is a detached view showing a modified form of the nozzle for injecting the charge or pulp.

Let A represent a vessel for containing the 60 fluid-charge or “pulp” bearing the metal to be extracted, and B a pump or other forcing apparatus by which the charge is injected into the amalgamating-vessel. These are simply indicated on the drawings, and on a small 65 scale, on account of the limited space. Any kind of vessel, of any size, may be employed to contain the charge, and any good pump of sufficient capacity may be used.

C is an amalgamating-vessel, which may be 70 of any suitable size or form and of any suitable material. I prefer, however, to employ a cylindrical vessel of iron for this purpose. This vessel is, or should be, in the present construction, closed at the top, and it is provided 75 with a perforated dispersing-diaphragm, D, and a bottom or base, E. This base, however, is only a convenience, and need not be considered as a separate element, as it might be simply a continuation of the vessel C. 80

F F represent the pipes for leading the charge from the vessel A or the forcing apparatus to the amalgamating-vessel. The large main pipe depends to a point over the center of the said vessel, and from this branch two or 85 more lesser pipes, which lead down the sides of the vessel and enter it near the bottom. The inner ends or nozzles, a a, of these pipes are directed upward at points between the periphery and the axis of the vessel, so as to deliver the 90 charge at several points in the mass of mercury. Where more than two inlet-pipes are employed, I arrange them, by preference, at points about equidistant around the vessel. The arrangement of the main pipe, as shown, enables me 95 to make all of the branch-pipes of equal length, thereby equalizing the friction of the passing current.

The mercury stands in the vessel C at about 100 the line x, and when the liquid charge is injected it rises to the top of the mercury, its entrance into the body of the mercury effectually preventing any sediment from collecting. The impetus it receives from the pump will

also greatly accelerate the speed of its passage. The charge thus introduced in jets or streams variously distributed is further dispersed in its passage through the diaphragm D, and all 5 its parts are thus brought more effectually and thoroughly into contact with the mercury. I may, however, dispense with the said diaphragm, or substitute for it a nozzle or nozzles for the pipe or pipes F, similar to that 10 shown in Fig. 2. This nozzle is made up of a series of short radiating pipes or tubes, g g, which deliver the charge into the mass of mercury in fine jets, and preferably in an upward direction.

15 Some particles of metal may, in passing through the vessel C, escape amalgamation from lack of proper contact from various causes, and to insure their being taken up I provide a second amalgamating-vessel, C', constructed 20 like that just described. This vessel I connect with the first by means of a pipe or pipes, F', which connect the vessel C near its top and above the line α with the mass of mercury in the vessel C', so that the charge, after passing 25 through the mercury in the first, may be caused to pass through that in the second vessel, as indicated. After it has passed through the mercury in the vessel C' it passes through a pipe, G, into a vessel or tank, H, which I call 30 a "concentrator." This concentrator, which is not, in itself, new with me, receives such particles of gold as will not amalgamate—as, for example, "rusty" gold and such particles of mercury as will have passed over—and these 35 will settle to the bottom of the concentrator, from which they may be removed from time to time. The operation is continued until the mercury in the vessel or vessels becomes too thick from its combination with other metals 40 to permit of carrying the process further, when the amalgam is drawn off at the valve or opening c at the bottom and a fresh charge of mercury inserted at d.

The charge in the vessel A is preferably 45 mixed only with water, and in this condition it passes through the vessel C; but I provide another vessel, I, containing a solution of potassium cyanide, and lead a pipe from this vessel to the pipe F', whereby I am enabled to 50 add this solution in regulated quantities to the charge as it passes to the vessel C'. This quickens and enlivens the mercury in the said vessel and enables it to act with more vigor on the particles of metal in the charge. I employ 55 this treatment in the vessel C' only for the sake of economy. It is not so necessary in the first amalgamating-vessel, as in this vessel all the free gold will be combined with the mercury without difficulty, and I aim to employ the cyanide treatment only on the charge containing 60 metals that have for various reasons escaped amalgamation under ordinary treatment. My method, therefore, relates to this form of treatment by means of the cyanide, and not to the 65 employment of the said salt generally in amalgamation.

To further accelerate the movement of the charge through the vessel C', I may arrange a suction-pump between the said vessel and the concentrator H, connecting it with the pipe G; 70 and I may employ two or more amalgamating-vessels arranged in a continuous system, as has been done; but I believe two will be enough to remove all of the metals capable of being amalgamated, especially when the cyanide 75 salt is employed in the second vessel.

Having thus described my invention, what I claim as new is—

1. The amalgamating process herein described, which consists in first passing the 80 metal-bearing charge through a body of mercury, then treating it with a solution of potassium cyanide, and then passing it, so treated, through another fresh body of mercury, substantially as set forth.

2. The combination, to form an amalgamating apparatus, of the elevated vessel containing the charge, the main pipe for the charge arranged to depend over the center of the amalgamating-vessel, the said amalgamating-vessel 90 having an overflow-outlet at the top, the branch pipes from the main pipe arranged to pass down at the sides of the amalgamating-vessel and to enter it radially, the said amalgamating-vessel and the several upturned nozzles of the 95 branch pipes arranged to deliver the charge upward into the mass of mercury at points between the periphery and the axis of the amalgamating-vessel, substantially as and for the purposes set forth.

3. The combination, to form an amalgamating apparatus, of the elevated vessel for the charge, means for forcing the charge or pulp into the mass of mercury in the amalgamating-vessel, the said amalgamating-vessel, the pendant pipe from the vessel containing the charge 105 with its branches, the latter arranged to pass down at the sides of the amalgamating-vessel and to pass through it into the mercury, the several upturned nozzles on said branch pipes 110 arranged under a perforated diaphragm in the amalgamating-vessel and the said diaphragm, all arranged substantially as herein set forth.

4. The combination, to form an amalgamating apparatus, of the vessel containing the 115 charge or pulp, the pipes for leading the charge to the first amalgamating-vessel, the two amalgamating-vessels and the pipe connecting them, the vessel for containing the potassium-cyanide solution, and the pipe connecting said vessel 120 with the pipe which leads the charge from the first to the second amalgamating-vessel, all arranged substantially as herein set forth.

In witness whereof I have hereunto signed my name in the presence of two subscribing 125 witnesses.

CHARLES C. BEERS.
